Machine Company, New York, N. Y., a corpora-
tion of Maine

Continuation of application Serial No. 210,318,
May 27, 1938. This application May 24, 1940,
Serial No. 337,062

10 Claims. (Cl. 112—123)

This application is a continuation of my prior application Serial No. 210,318, filed May 27, 1938.

The invention relates to a pinking attachment for use with sewing machines and an object thereof is to provide a pinking attachment which will more suitably pink materials simultaneously with the sewing thereof and especially for the production of an edge-folded, topstitched seam.

Another object of this invention is to provide a pinking attachment having a movable cutter which is pivotally sustained below the base of the sewing machine and which is actuated in a manner as to leave the upper surface of the sewing machine base clear for operating purposes.

Another object of this invention is to provide a pinking attachment of the character described, which is driven by mechanism designed for actuating the movable cutting element at predetermined intervals in timed relation with the needle.

Another object of this invention is to provide a pinking attachment having a male cutter carrier rearwardly of both the hook-driving shaft and the needle, the carrier being pivotally sustained at one end of a lever positioned longitudinally below the base of the sewing machine.

Another object of this invention is to provide a pinking attachment having a female cutter mounted level with the cloth plate of the sewing machine and having an actuating lever for the male cutter mounted wholly below the base plate of the sewing machine and comprising a male cutter carrier rearwardly of both the hook-driving shaft and the needle, the cutter carrier having its lower end pivotally sustained at one end of the lever, and the base plate having an opening to permit the male cutter carrier and male cutter to pass upwardly above the base plate with the male cutter in cutting engagement with the female cutter.

The above and other objects of the invention will be apparent from the detailed description of the combination and arrangement of parts shown in the accompanying drawings wherein like numerals of reference designate corresponding parts through the several views and in which:

Figure 1 is a front elevation, with parts broken away, of a sewing machine having my pinking attachment applied thereto.

Fig. 2 is a plan view of the pinking attachment and associated parts.

Fig. 3 is a side view of the pinking attachment shown in Fig. 2.

Fig. 4 is an end view of the structure shown in Fig. 2.

Fig. 5 is a plan view of pieces of fabric united by an edge-folded and top-stitched seam made with the pinking mechanism of my invention.

Fig. 6 is a fragmentary top plan view of a portion of the sewing machine having the pinking mechanism applied thereto.

Fig. 7 is an end view of the parts shown in Fig. 6.

In the illustrated embodiment of the invention, the numeral 10 indicates a sewing machine comprising a base-plate 11, and an overhanging arm 12 having a head 13 at its free end. A main actuating shaft 14 mounted in the arm 12 through suitable connections imparts vertical reciprocatory movements to the needle-bar 15 whereby the needle 16 is reciprocated once for every rotation of the main shaft 14.

Secured to the base-plate 11 so as to lie flush with the top thereof is a cloth plate 17 having a needle opening and feed slots for a feed dog 18, the needle being timed to cooperate with a hook or loop-taker 19 for the purpose of forming stitches, the hook or loop-taker being driven by a shaft 19'. A presser-foot bar 20 is yieldably supported in the head 13 and carries a presser-foot 21.

The numeral 25 indicates my pinking attachment as a whole, comprising a base 26 having a depending post 27 which is slotted at its lower end to receive a lever 29. The lever is pivotally mounted on a bearing pin 30 in the post 27. The base-plate 11 has an aperture 28 to permit passage therethrough for the post.

The front end of the lever 29 is bifurcated to form two arms 32, 32, for a cutter carrier 33 which is pivotally mounted on a bearing pin 34 extending through said arms.

A male cutting member 35 of generally triangular prismatic form is fastened to the cutter carrier 33 by means of a bolt 36. A female cutting member 37 is fastened to the lower surface of the base 26 and has therein a V-shaped opening 38, and is provided with upwardly extending guide members 39, 39' forming continuations of and having the same inclination as the sides of the V-shaped opening 38. The guide members 39, 39' are spaced away from the apex of the opening 38 and extend upwardly a distance sufficient so as to be constantly in engagement with the rear portions of the cutting walls of the male cutting member 35, under all operating conditions, and serve to maintain the male and female cutting members in alinement.

A ribbon-like leaf spring 41 is fastened to the lever 29 by means of a screw 42 and extends angularly against the male cutter carrier 33 and serves to bias the male cutter outwardly about the pin 34 into engagement with the female cutting member 37.

The pressure exerted by the leaf-spring against

the male cutting member serves to press the cutting edges of the cutting members together so as to be adaptable for cutting fabrics of various thicknesses.

Figure 1 shows my pinking attachment 25 mounted on the base plate 11 of the sewing machine 10 and is rigidly attached thereto by means of bolts 43 passing through elongate apertures 44 in the base 26. It will be noted that the cloth plate 17 of the sewing machine 10 is cut away at one side to permit the female cutter which is disposed rearwardly of the needle to come close to the stitch line of the needle and that the front end of the female cutter lies flush with said cloth plate. It will be noted that by partially unscrewing the bolts 43, it is possible to slide the pinking attachment 25 longitudinally and thus vary the distance between the stitch line formed by the needle 16 and the ornamented edge of the fabric formed by the pinking or cutting members 35 and 37. As shown in Figure 2, the pinking or cutting members 35 and 37 are always disposed so as to cut in a plane transverse to the line of feed or stitch line formed by the needle 16.

The lever 29 at its rear end carries a pin 45 which is ball-jointed at 45 to a link 50 through a divided ball housing 50'. The upper end of the link 50 is mounted on a bearing pin 51 at one end of a transverse shaft 55. The actuating mechanism which causes the lever 29 of my pinking attachment 25 to swing about the bearing pin 30 comprises the shaft 14, a worm 53 fixed thereon and a worm gear 54, carried by the transverse shaft 55.

The transverse shaft 55 is geared to rotate at a lower number of revolutions than the shaft 14. The shaft 55 has an eccentric portion forming the bearing pin 51 on which the upper end of the link 50 is mounted. It will thus be noted that the link 50 being in engagement with the pivotally mounted lever 29 will cause the lever to swing up and down about the bearing pin 30, solely due to the motion of the main shaft 14, and during operation, the cutting mechanism will come into pinking engagement a lesser number of times than the number of stitches formed by the needle 16.

It is to be noted that the link 50 has a left hand thread at its upper end and a right hand thread at its lower end. The oppositely directed threads make it possible, by rotating the member 50, to lengthen or shorten the distance between the centers of the bearing pin 51 and the ball junction 45, 50' and thereby provide for raising and lowering the male cutting member 35 and adjusting it after being ground for wear.

As shown in Figures 2 to 4, inclusive, I have provided a stripper plate 56 which is mounted in slightly spaced relation above the female cutting member 37 and has an inclined wall 57 in alignment with the front side of the V-shaped opening 38. The stripper plate 56 is fastened to the base plate 11 and serves to strip the fabric worked upon from the cutting member 35.

The inclined wall 57 has a substantial height. When making an edge-folded and topstitched seam, one fabric section rides on the wall 57 to a sufficient height so as to pass easily over the top of the cutting member 35.

Figure 5 shows an edge-folded and topstitched seam 60 comprising two sections of fabric 61 and 62 seamed together with a single row of topstitching 63 and having a pinked edge 64. The top section of fabric 62 has its edge folded and the two sections 61 and 62 are fed to the needle 75

and to the pinking mechanism through a suitable folder indicated as a whole by the reference 65, shown in Figures 6 and 7.

The folder 65 includes an attaching plate 66 which is adjustably secured to the base plate 11 by means of a screw 67. An inside folding plate 68 and an outside folding plate 69 are secured to the plate 66 such as by soldering to an upwardly bent extension 74. The plate 68 is bent downwardly and inwardly and forms a rolled edge 70 about which the upper fabric section 62 folds.

Extending substantially parallel to the rolled edge 70 of the inside folding plate 68 is a fabric separating plate 71 which forms part of the outside folding plate 69.

The folding plates 68 and 69 converge as they approach the needle 16. The end 72 of the plate 68 extends under the presser-foot 21 which is undercut at 73 (Figures 1, 6 and 7) to permit the end 72 to come close to the needle.

As the two sections of fabric leave the rear of the folder 65 they pass between the presser-foot 21 and the cloth plate 17 to be stitched together and pinked, the section 62 sliding over the top surface of a cover plate 75 mounted above the base plate 11. The cover plate extends above the male cutting member 35 and shields the fabric section 62 from being dragged under the male cutting member and damaged.

The needle 16 passes through the double thickness of the section 62 and through the single thickness of the section 61, stitching the two sections together and the folded edges of the stitched sections pass between the cutting members 35 and 37 and produce the pinked, edge-folded and topstitched seam shown in Figure 5 in a single operation.

It is to be noted that while I have shown the cutting members as positioned considerably to the rear of the needle 16, that I may mount the pinking attachment with the cutting members in line with the needle. I may also secure the post 27 to the lower surface of the base plate 11 and do away with the base 26 of the pinking attachment and leave substantially the entire upper surface of the sewing machine base plate free for operational purposes.

In the arrangement herewith shown, the male cutting member 35 is designed to cut on the downward stroke. I may however reverse and suitably position the female cutting member 37 so as to cause the male cutting member to cut on the upward stroke.

While I have shown and described a preferred embodiment of my seaming and pinking attachment, it will be understood that changes in the specific details of construction may be made within the scope of the following claims without departing from the spirit of my invention.

What I claim is:

1. In a combined seaming and pinking machine, driving mechanism, a work supporting base, male and female pinking cutters, one of which is substantially vertically reciprocable, a carrier for the reciprocable cutter, a lever at one end of which the cutter carrier is pivotally sustained for substantially vertical reciprocatory movement, said lever being fulcrumed intermediate its ends to a support positioned below the work supporting base and means actuated by the sewing machine driving mechanism for actuating the lever to reciprocate the cutter.

2. In a combined seaming and trimming machine, driving means, a work supporting base, a

vertically reciprocating needle, a hook driving shaft, a pinking attachment comprising male and female pinking cutters, one of which is substantially vertically reciprocable, a pivoted lever below said base, a cutter carrier for the male cutter pivotally sustained at one end of said lever rearwardly of said needle, and means actuated by the sewing machine driving means for actuating the other end of said lever in timed relation to the needle reciprocations.

3. In a combined seaming and trimming machine, driving means, a work supporting base, a vertically reciprocating needle, a hook driving shaft, a cutter carrier, a pinking attachment base attached to said sewing machine base and having a pivotal support extending downwardly, a lever mounted in said pivotal support below said base, said cutter carrier being pivotally sustained at one end of said lever rearwardly of said needle, and means actuated by the sewing machine driving means for actuating the other end of said lever in timed relation to the needle reciprocations.

4. In a combined seaming and trimming machine, driving means, a work supporting base, a vertically reciprocating needle, a pinking attachment having a base attached to the base plate of the sewing machine and disposed at one side of the needle and having a female cutting member fastened to the base of the pinking attachment, a hook-driving shaft mounted below said base, a male cutter carrier positioned rearwardly of said hook driving shaft, a lever and a pivotal support for said lever positioned below said base, said male cutter carrier being pivotally sustained at one end of said lever rearwardly of said needle, and means actuated by the sewing machine driving means for imparting cutting movements to said male cutter in timed relation to the needle reciprocations.

5. In a combined seaming and trimming machine, driving means, a work supporting base, a vertically reciprocating needle, a hook driving shaft, a pinking attachment having a base attached to the base plate of the sewing machine and disposed at one side of the needle and having a female cutting member fastened to the base of the pinking attachment, a hook driving shaft mounted below said work supporting base, a male cutter carrier offset rearwardly of the hook-driving shaft, a lever pivotally supported below said work supporting base, said male cutter carrier having its lower end pivotally sustained at one end of said lever rearwardly of said needle, a spring for biasing said male cutting member into engagement with said female cutting member, and means actuated by the sewing machine driving means for imparting cutting movements to said male cutter in timed relation to the needle reciprocations.

6. In a combined seaming and trimming machine, driving means, a work supporting base, a vertically reciprocating needle, a hook driving shaft, a pinking attachment having a base attached to the base plate of the sewing machine and disposed at one side of the needle and having a female cutting member fastened to the pinking attachment base, a hook-driving shaft mounted below said work supporting base, a male cutter carrier positioned in rearwardly offset relation to said hook-driving shaft, a lever pivotally supported below said work supporting base, said male cutter carrier having its lower end pivotally sustained at one end of said lever rearwardly of said needle, said base plate and pink-

ing attachment base having openings to permit said cutter carrier to pass upwardly above said female cutting member, spring means biasing said cutter carrier for yieldingly forcing said male cutting member into cutting engagement with said female cutting member, and means actuated by the sewing machine driving means for imparting cutting movements to said male cutter in timed relation to the needle reciprocations.

10 7. In a combined seaming and pinking machine, driving means, a work supporting base, a cloth plate, a stitching needle reciprocable perpendicularly to said base, a pinking attachment having a base disposed at one side of the needle, 15 a female cutting member fastened to the pinking attachment base, a hook-driving shaft mounted below said work supporting base, a lever pivotally supported below said hook driving shaft, a male cutter carrier having its lower end pivotally sustained at one end of said lever rearwardly of said needle, said cutter carrier having a cutter supported at its upper end, said base plate and pinking attachment base having openings to permit said male cutting member to pass upwardly above said female cutting member, 20 spring means for yieldingly biasing said male cutting member into cutting engagement with said female cutting member, means in spaced relation above said female cutting member for stripping the pinked fabric from said male cutting member, and means actuated by the sewing machine driving means for imparting cutting movements to said male cutter.

8. In a combined seaming and pinking machine, driving means, a work supporting base, a head having a needle and a main shaft, male and female pinking cutters, one of which is substantially vertically reciprocable and positioned rearwardly of said needle, a carrier for the reciprocable cutter, a lever at one end of which the cutter carrier is pivotally sustained for substantially vertical reciprocatory movement, said lever being fulcrumed intermediate its ends to a support positioned below the work supporting base 45 and means actuated by the sewing machine driving mechanism for actuating the lever to reciprocate the cutter, said means comprising an adjustable upright link, one end of which is ball-jointed to one end of the lever and the other end 50 of which is operatively connected to said main shaft.

9. In a combined seaming and pinking machine, driving mechanism, a work supporting base, a female cutter, a substantially vertically 55 reciprocal male cutter, arranged to effect a cut on the downward stroke, a carrier for the male cutter extending below the work supporting base, a lever at one end of which the cutter carrier is pivotally sustained, said lever being pivoted to a support below the base, and means actuated by the sewing machine driving mechanism for actuating the lever to reciprocate the cutter.

10. In a combined seaming and pinking machine, driving mechanism, a work supporting base, a female cutter, a V-shaped male cutter arranged to coact with the female cutter to effect a cut on the downward stroke, a pivoted lever below the work supporting base, a cutter carrier for the male cutter pivotally sustained at one end of said lever and arranged to project the male cutter through the female cutter, and means actuated by the driving mechanism for actuating the lever to reciprocate the cutter.
